CLOSURE MEANS FOR HERMETICALLY
SEALED JARS

Randolph H. Barnard, Toledo, Ohio, assignor to
Vacuum Seal Company, Inc., New York, N. Y.,
a corporation of New York

Application August 27, 1932, Serial No. 630,681

2 Claims. (Cl. 215—47)

The present invention is an improvement in jars of the type disclosed in Patent No. 1,212,274, granted January 16, 1917, in which a packing ring of rubber or analogous material is compressed between specially shaped surfaces of the jar body and its cap or closure member, and prevents air leakage through the joint between said member and jar into the air exhausted interior of the jar.

10 The present invention is characterized by a packing ring engaging surface on the jar body which is additional to those disclosed in said prior patent, and which is so shaped and disposed as to attain objects and secure advantages of substantial practical importance, as will be recognized by those skilled in the art from the accompanying drawing and descriptive matter in which I have illustrated and described a preferred embodiment of the present invention.

15 Of the drawing:

Fig. 1 is a vertical central section of an all glass preserving jar or vessel with its closure parts in place as when sealed;

Fig. 2 is a plan view of the jar shown in Fig. 1;

Fig. 3 is a section of the gasket or sealing ring in its initial condition; and

Fig. 4 is an enlarged scale reproduction of a portion of Fig. 1.

In the embodiment of the present invention illustrated in the drawing, the seal ring engaging surface of the jar 1 comprises a jar end portion 2 at the margin of and surrounding the jar mouth, and portions 3, 4, 5 and 6 successively more remote from the end of the jar.

When the jar is in its upright position in which it is normally filled and sealed, the surface 2 is horizontal or approximately so, the surfaces 3 and 6 are vertical, or approximately so, the surface 4 is inclined to the vertical at an angle of 40 degrees, or so, and the surface 5 is inclined at a substantially greater angle to the vertical and in practice may well be horizontal or approximately so.

The jar cap or closure 7, which, like the jar body 1, is usually formed of glass, comprises a rim or circumferential flange portion 8 surrounding a body portion 9, and is so shaped and proportioned that when the cap is in its normal jar closing position, the flange 8 overlies the end surface of the jar, while the body portion 9 extends into the mouth of the jar far enough to overlap the jar surface portion somewhat. The outer surface of the body portion 9 is then vertical or approximately so, and the under surface of the flange 8 is horizontal or approximately so. In

ordinary practice, and as shown, the mouth of the jar is circular in outline and the outer surface of the cap portion 9 and the jar surfaces 3 and 5 are approximately cylindrical, while the surface 4 is conical. While the outer surface of the cap portion 9 and the surface 3 may each be truly vertical, in ordinary practice the outer surface of the cap 9 is inclined downwardly and inwardly at an angle of a couple of degrees or so to the vertical to facilitate the lid formation in a glass molding machine and this taper is also beneficial in its resulting wedging action on the seal ring. Similarly, to facilitate the manufacture of the jar, the surface 3 is ordinarily inclined upwardly and away from the vertical at an angle of a couple of degrees or so.

The sealing ring 10 is formed of pure rubber or analogous material, and, when in its initial uncompressed condition, is ordinarily of rectangular cross section as shown in Fig. 3. The ring 10 surrounds, and is of an internal diameter to fit snugly over the portion 9 of the cap 7, and is of an exterior diameter permitting its easy entrance within the surface 3 forming the wall of the enlarged outer portion of the jar mouth.

In the sealed condition of the jar with the air exhausted from the interior of the latter, the atmospheric pressure acting on their outer surfaces forces the jar body and cap 7 together so that the sealing ring 10 is compressed and distorted into the general form shown best in the enlarged section 4. As shown in Fig. 4, the pressure to which it is subjected radially expands the outer portion of the ring so that a flange-like portion of the ring is compressed between the jar end surface 2 and the cap rim portion 8, while an inner edge portion of the ring is extruded into the upper portion of the space between the cap portion 9 and the jar surface 6. In the normal sealed condition shown in Fig. 4, the major intermediate portion of the ring is compressed into snug contact with, and entirely fills the space between the jar surface portions 3 and 4 and the cap portion 9.

As shown, the rim portion 8 of the cap 7 is formed with a notch to permit the insertion of an implement for displacing the packing ring 10 sufficiently to break the vacuum within the jar when the latter is to be opened.

The surface 5 added, in accordance with the present invention, to the jar shown in said prior Patent No. 1,212,274, increases the effectiveness of the jar closure and minimizes its liability to failure under certain adverse conditions, and permits the surface 4 to be inclined to the vertical at a smaller angle than would otherwise be re-

quired, and thereby facilitates and reduces the cost of manufacture of the jar body.

The addition of the surface 5 directly adds to the effectiveness of the closure seal by increasing the tortuosity of the path along which leakage, if any, between the jar surfaces and the sealing ring 10 can occur. The surface 5 and the subjacent surface 6 unite to form a corner 11, which engages or bites into the seal ring material extruded inwardly past the surface 5, and which more effectively restrains the latter against any tendency to outward movement than does the more obtuse corner formed with the construction of said prior patent, at the intersection of the jar surfaces thereof which correspond generally to the surfaces designated 4 and 6 herein. The seal ring retaining effect of the corner 11 is especially useful under such adverse conditions as prevail, for example, when sealed jars are transported for long distances in railroad cars, and are thereby subjected for relatively long periods to rapidly repeated shock or vibration stresses.

The improved ring retaining action of the relatively sharp corner formed at the intersection of the surfaces 5 and 6 of the present construction is of especial importance because it makes it practically possible to decrease the angle of inclination to the vertical of the surface 4. In practice, the said angle in jars constructed in accordance with the present invention, is normally made 40°, with a permissible departure tolerance of 5° in each direction. With the construction shown in said prior patent, it has been found necessary in commercial practice to make the corresponding angle 45°, with a similar permissible tolerance of departure of 5°. In the practical manufacture of jar bodies in automatic glass molding machines, the decrease in said angle to the vertical from a normal value of 45° to a normal value of 40°, materially facilitates the production of jars in which the main wedge sealing surface, designated 4 herein, is sufficiently free from crizzles, checks, or cracks tending to cause leakage, and reduces the number of jars which cannot pass inspection and must be discarded because of such defects.

While I have herein shown a preferred embodiment of my invention by way of illustration

and example thereof, it is evident that some changes may be made therein without departure from the spirit of the present invention as set forth in the appended claims.

Having now described my invention, what I desire to secure by Letters Patent is:

1. In a device of the character described comprising a vessel having an opening bounded by an outer substantially vertical surface and an adjoining inwardly inclined tapering surface, a cover having an overhanging flange and an underlying substantially vertical surface, and a packing ring engaging said surfaces and flange and compressed between the cover and vessel into an outer portion of wedge-shaped section extending between said inwardly tapering surface and said substantially vertical cover portion, and an inner portion extending along said cover surface at the inner side of said inclined surface, the improvement which consists in an inwardly extending vessel surface at the inner side of said inclined surface and inclined to the vertical at a substantially greater angle than said tapered surface and terminating in a corner edge surrounding and spaced away from the said cover surface. 90

2. In a device of the character described, a vessel having an opening bounded by an outer substantially vertically extending surface, an adjoining inwardly inclined tapering surface, a substantially horizontal surface intersecting said inclined surface at the inner edge of the latter, and an inner substantially vertical surface which at its outer edge intersects said transverse surface to form a corner, a cover having an overhanging flange and an underlying substantially vertical surface the inner portion of which extends alongside of and is spaced away from said inner substantially vertical surface of the vessel and a packing ring engaging said surfaces and flange and having its outer portion compressed to a wedge-shaped section by contact with said inwardly tapering surface and having an inner portion compressed into and filling the outer portion of the space between the portion of said cover at the inner side of said corner and the adjacent portion of the vessel. 110
